UNITED STATES PATENT OFFICE

100,961

DESIGN FOR A CAMERA

Joseph Mihalyi, Rochester, N. Y., assignor to Eastman Kodak Company, Rochester, N. Y., a corporation of New York

Application February 29, 1936, Serial No. 61,431

Term of patent 14 years

To all whom it may concern:

Be it known that I, Joseph Mihalyi, a citizen of the United States, residing at Rochester, in the county of Monroe and State of New York,
have invented a new, original, and ornamental Design for a Camera, of which the following is a specification, reference being had to the accompanying drawing, forming a part thereof.

In the drawing:

Fig. 1 is a front elevation showing a camera
embodiment my new design.

Fig. 2 is a perspective view of the camera

shown in Fig. 1, showing a part of the side and top.

Fig. 3 is a perspective view of the camera
shown in the preceding figures in an open or picture-taking position.

The carrying strap shown in Fig. 3 has been omitted from Figs. 1 and 2 for convenience of illustration.

I claim:

The ornamental design for a camera as shown
and described.

JOSEPH MIHALYI.
